UNITED STATES PATENT OFFICE

ROY W. BROWN, OF AKRON, OHIO, ASSIGNOR TO THE FIRESTONE TIRE & RUBBER COMPANY, OF AKRON, OHIO, A CORPORATION OF OHIO

MOLD SERVING DEVICE

Application filed February 23, 1930. Serial No. 432,022.

This invention relates to means for opening or cracking molds particularly of the individual watchcase type adapted to cure pneumatic tires.

It is an object of the invention to provide mold cracking means which serve a plurality of aligned individual molds.

It is a further object of the invention to provide means adapted to crack the mold and lift the upper half thereof to a position which permits the cured article to be removed and a fresh article substituted.

Again, a more particular object of the invention resides in providing semi-automatic mold cracking and lifting means arranged to quickly and effectively serve and handle parallel rows of individual molds.

The above and other objects of the invention are attained by the apparatus illustrated in the accompanying drawings and described below, it being understood that the invention is not limited to the specific form thereof shown and described.

In the drawings:

Figure 1 is a plan view partly broken away of the mold cracking means embodying the invention.

Figure 2 is a side elevation partly broken away of the apparatus illustrated in Figure 1.

Figure 3 is an end view partly broken away of the apparatus shown in Figure 1.

Figure 4 is a schematic wiring diagram of the various switches, motors, etc., included in the invention.

Referring to the drawings, a plurality of tire molds 10 of the watchcase type are arranged in parallel rows as shown in Figure 1 below a pair of tracks 11 formed by suitable means such as I beams. The tracks 11 carry a mold cracking and lifting device which includes a bridge 15 which may be strengthened by raised ribs 15^a. The bridge 15 is given a three-point suspension by extending it at 15^b and pivotally attaching an axle bar 17 to the extended portion by a pin bolt 18. Wheels 19 journaled at the ends of the axle bar 17 and on the end of the bridge 15 opposite the axle bar slidably support the bridge on the tracks 11. In order to control

the position of the bridge 15 on the tracks 11, a rack 20 is fixed to each track and a reversible motor 21 on the bridge 15 is arranged through the agency of a worm drive 22 to drive pinions 23 which engage with the racks 20 to propel the bridge in either direction along the tracks. A standard spring magnetic brake 24 is preferably provided on the drive shaft of the motor 21. This brake is of the type which is engaged or operative as long as no current is flowing to the motor 21, but which releases when the motor is started as current also flows to the solenoid of the brake to lift it out of engagement against the action of a spring which normally holds it in engagement.

A carriage 25 is rotatably carried by a stud bolt 26 below the bridge 15. Fixed to the upper surface of the carriage 25 is a circular rack 27 with which engages a pinion 28 driven through a spring-held slip clutch 29 by a reversible motor 30. Journaled as at 31 on the lower end of the carriage 25 is an arcuate crane arm 32 which carries a pair of curved racks 33 on its outer surface. Pinions 34 mounted on a shaft 35 and driven by a reversible motor 36 through the agency of worm gearing 37 cooperate with the racks 33 to control the position and movement of the crane arm 32. A magnetic brake 38 similar to the brake 24 is provided in the drive of the motor 36.

Pivotedly carried on a shaft 40 at the end of the crane arm 32 is a chuck 41 which is adapted to engage with the upper half of the mold 10 as indicated at 42. The jaws of the chuck 41 are controlled by a handwheel 43 as will be understood. Means, such as a bar 44 on the mold 10, are adapted to cooperate with brackets 44^a on the carriage 25 to guide the upper mold half as it is being raised.

In order to supply the motors with current spaced trolley wires 45 are held adjacent the tracks 11 and trolleys 46 are provided to engage therewith.

In its preferred form the invention contemplates semi-automatic features of control which may be widely varied to suit the individual needs of each installation. In the embodiment of the invention illustrated such

means include a main control box 50 fixed to the bridge 15. A push button station 51 may also be placed in more immediate relation to the operator if desired. Whereas the motors 5 are ordinarily started by hand from one of the push buttons, a number of limit switches operated by cams are provided to automatically stop the motors. A cam 52 engages with a limit switch 53 to stop the crane arm 32 in its uppermost position. A similar cam 54 10 engages with a limit switch 55 to limit the downward movement of the crane arm. A cam 56 cooperating with a switch 57 is adapted to stop the crane arm in an intermediate position when desired.

To render the apparatus fool-proof a pair of normally open interlock switches 60 and 61 may be provided adjacent the crane arm 32, the switch 60 being closed only when the arm 20 is in its intermediate position and the switch 61 only when the arm is fully raised by a suitable cam 62 on the crane arm. The interlock switches 60 and 61 are connected in the circuit of the motors 21 and 30 respectively 25 so that it is impossible to operate either motor unless the crane arm is in the raised or intermediate position. Mounted on the bridge 15 on a raised platform 64 is a third normally open interlock switch 65 which is closed 30 by a fixed cam 66 duplicated at each mold station only when the bridge is above a mold so that it is impossible to operate the crane arm up and down when the bridge is moving from one mold to another.

The platform 64 also serves to mount six limit switches which serve in the following manner: Switch 68, final travel in one direction; switch 69, final travel in the other direction; switch 70, stop at each mold one direction; switch 71, stop at each mold other direction; switch 72, really a double switch, slow just before each mold going one direction; switch 73, really a double switch, slow just before each mold going other direction. 40 Cams (not shown) are provided at either end of the track 11 to operate the limit switches 68 and 69 at the complete end of the bridge travel. This normally never occurs and is merely a safety feature. A cam 75, which is 45 duplicated at each mold station, serves to slow down the motor 21 while a cam 76, also duplicated at each station, serves to stop the bridge at each mold station. Cams similar to cams 75 and 76 are provided (not shown) for the 50 switches 71 and 73 when the bridge is moving in the other direction.

Adjustable positive stops 80 may be provided on the bridge 15 which engage with lugs 81 on the carriage to limit its rotation. 55 When the lug 81 engages the stop 80 the spring clutch 29 in the motor drive is adapted to slip preventing breakage. This however, increases the motor load which kicks out standard overload relays (not shown except 60 in Figure 4) to stop the motor 30.

In Figure 4 the numerals 91 and 92 indicate a plurality of contacts normally held in the open position. A solenoid 91^a in the control circuit is provided to hold the contacts 91 closed when it is energized. A solenoid 92^b is also provided to hold the contacts 92 closed. The contacts 91 and 92 are actually a triple pole, double throw switch so that it is impossible to hold both sets of contacts together at the same time. When the contacts 92 are closed the motor 36 is moving the crane arm downwardly to close the mold. In this circuit are placed standard thermal overload relays 95 which are adapted to kick out to stop the motor 36 if the limit switch 55 fails to operate or if the mold is fully closed before the limit switch is reached or the like. The relays 95 break the control circuit at 95^a. Hand reset ultimate overload relays 96 opening the circuit as at 96^a may also be provided in this motor circuit as an added protection. The closing solenoid 92^b also serves to close a switch 92^b of the holding circuit which allows the operator to remove his hand at once from the close push button 97.

For safety purposes the control circuit is also provided with a resetting solenoid 98 which closes a switch 98^a by pushing either resetting button 99 located on opposite sides 95 of the control box 50.

The control circuit for the motor 36 also includes a solenoid 100 which is adapted to hold switches 100^a and 100^b open and switch 100^c closed when it is not energized and to hold switches 100^a and 100^b closed and switch 100^c open when it is energized. A solenoid 105 is also provided to hold switch 105^a closed when it is energized. The circuit also has a fully open push button 106, an intermediate open push button 107, a stop button 108 and the fully open limit switch 53, the close limit switch 55, the intermediate open limit switch 57, the interlock 65 and the brake 38 all hereinbefore described.

The control for the motor 21 includes a double pole, double throw switch indicated at 110 which is controlled by a pair of solenoids 111^a and 112^a so that either contacts 111 or contacts 112 are closed. When neither solenoid is energized all the contacts are open. The solenoid 112^a is also adapted to hold a switch 112^b and a switch 112^c closed when it is energized. The solenoid 111^a in a like manner holds a switch 111^b and a switch 111^c closed when energized. The motor 21 is provided with both high and low speed shown at 113 and 114 respectively, and a triple pole double throw switch indicated at 115 is arranged to connect the supply leads to the one or the other thereof. A solenoid 116^a is arranged to close the switch 115 to the low speed position and a solenoid 117^a to close the switch 115 to the high speed position.

This motor control circuit also includes a

plurality of single pole double throw switches 120^a, 120^b, 120^c and 120^d operated by a pull switch 121 (see control box 50), so that the apparatus can be operated from either side of the double row of molds 10. A single pole single throw switch 120^e is closed when the switches 120^a, 120^b, 120^c and 120^d are on the upper contacts and a single pole single throw switch 120^f is closed when the switches 10 are down.

Automatic means are arranged to start the motor 21 to move the bridge to the next mold when the intermediate button has been pushed and the crane arm has been raised to the intermediate position where the interlock 60 has been closed by the cam 62. The current flowing through the traverse solenoid 105 not only serves to hold in the switch 105^a but also a switch 105^b, thus causing the traverse motor 21 to move the bridge to the next station. The interlock 60 must engage shortly before the intermediate limit switch 57 breaks the circuit to the traverse solenoid 105 as will be evident.

The remaining apparatus in the traverse motor circuit includes a forward push button 125, a reverse push button 126, a stop push button 127, a resetting safety device similar to that in the circuit of motor 36, comprising solenoid 130, which closes a switch 130^a by pushing either button 131, an overload relay 132 breaking the circuit at 132^a, the brake 24 and the slowing down switches 72 and 73, the individual stop switches 70 and 71 and the final stop switches 68 and 69. From the diagram it will be seen that when the slowing down switches are operated the current is supplied to the low speed leads of the motor, whereas it had been supplied to the high speed leads.

The control for the motor 30, which is adapted to rotate the carriage 25 supported on the bridge 15, includes a triple pole, double throw motor reversing switch 135, having two sets of engaging contacts 136 and 137. A solenoid 136^a is adapted to close the contacts 136 as well as hold in a switch 136^b. A solenoid 137^a is also provided to close the contacts 137 and a switch 137^b. A single pole double throw switch 120^g operated by the pull switch 121, aforementioned, is arranged in the circuit as shown.

A thermal overload relay 140 opening the circuit as at 140^a is provided to open the motor circuit as the spring clutch 29 starts to slip when the lug 81 engages with the stop 80. An ultimate overload relay 141 may also open the circuit at 141^a if desired. The other apparatus in the circuit includes right push buttons 142, left push buttons 143, interlock 61, and stops 144.

It is believed the operation of the apparatus will be apparent from the foregoing description, however, the operation is briefly as follows: The cure having been completed in

the mold 10, the pull switch 121 is first pulled to throw all the switches 120 in one direction (assume it closes the switches 120 upwardly in Figure 4) so that the apparatus is operated from one side then, the close button 97 is pushed which starts the motor 36 and moves the crane arm 32 down so that the chuck 41 engages in the hole in the mold 10. The limit switch 55 is now operated by the cam 54 to stop the motor 36 and the crane arm 32. If the limit switch 55 fails to operate due to variations in the molds or other causes the relay 95 will operate due to the increased load at the time the crane arm will move no further. The relay 96 will also operate if the relay 95 fails to function.

The handwheel 43 on the chuck 41 is rotated to lock the chuck in the mold and the fully open push button is pressed which reverses and starts the motor 36, thus cracking the mold. The upper mold half is first moved upward and then swung through an arc after the means 44 and 44^a engage. The cam 52 engages with the limit switch 53 to stop the upward travel of the crane arm. The molded article can now readily be removed and replaced with a green or unvulcanized one. The close button is again pushed which closes the mold as before. The chuck wheel 43 is rotated to the open position and the intermediate open button 107 is pushed which raises the crane arm until the interlock 60 is closed by the cam 62 which energizes the traverse motor 21 to move the apparatus to the next mold where it automatically stops when the switch 70 is opened by the cam 76.

When the fully open push button is operated the closing of the interlock 60 by the cam 62 has no effect as no current flows through the traverse solenoid 105 as will be evident from a study of Figure 4. The motor 21 has been thrown to the low speed leads when the cam 75 engages the slow down limit switch forward 72 as explained heretofore. In the meantime immediately after the interlock switch 60 has been thrown the intermediate limit switch 57 is opened by the cam 56 to stop the upward movement of the crane arm 32.

This operation is repeated at each mold station. The final limit switches 68 and 69 prevent the apparatus from accidentally overrunning and crashing into the end of the tracks. When the end of the row of molds is reached and the last mold refilled and closed instead of pushing the intermediate open button the fully open button is pushed and the crane arm is raised to the fully open position, where it is automatically stopped as before. However, in this position of the crane arm the interlock switch 61 is closed by the cam 62 which allows either the right 142 or the left push button 143 to be operated which energizes the motor 30 to rotate the carriage 25 around so that the chuck 41 of

the crane arm is in vertical alignment with the first mold in the second row of molds. At this time the motor 30 is stopped when the stop 80 and the lug 81 engage to cause the spring clutch 29 to slip which overloads and stops the motor through the agency of the overload relays 140 or 141.

Before the apparatus is operated on the second row of molds the pull switch 121 is 10 pulled to throw all the switches 120 the other way (downwardly) so that the apparatus can be operated along the second row of molds from the other side of the control box 50. The operation on this side is similar to that 15 above described and when the end of the row of molds is reached the carriage 25 is operated to again swing the chuck 41 back over the first row of molds. In this manner a double row of molds is quickly and effectively 20 served and handled in a semi-automatic way which lowers production and labor costs while insuring a more uniformly cured article of manufacture.

While the invention is particularly adapted 25 to serve individual tire molds, it also contemplates operating molds of any type adapted to manufacture a plurality of articles formed from various materials.

The invention also contemplates forming 30 the tracks 11 in closed paths and arranging the molds to cooperate therewith. Also the number of parallel rows of molds can be increased as can the length of the crane arm 32 so that one serving apparatus will serve 35 more molds.

As many other changes could be made in the construction, particularly in regard to the details of the wiring diagram and to the automatic features including the limit 40 switches and the operating cams, it is intended that all matter contained in the above description or shown in the accompanying drawings shall be interpreted as illustrative only and not in a limiting sense, accordingly 45 modifications and applicatons of the invention can be resorted to without departing from the spirit of the invention or the scope of the appended claims.

What is claimed is:

50 1. In combination, a plurality of aligned molds arranged in two parallel rows, a pair of tracks above said rows of molds, a bridge, means adapted to give said bridge a three-point rolling suspension on said tracks, a carriage, axial means for pivotally supporting said carriage below said bridge, an arcuate crane arm pivotally carried at the axis of its arc on the lower end of said carriage, a rack on the arcuate surface of said arm, a pinion on said carriage adapted to engage with said rack, a motor to control said pinion and thus the position of the crane arm, a vertically extending chuck pivotally mounted at the end of said crane arm and adapted to engage in openings in said molds, and interlocking means on said chuck and in the mold openings.

2. In combination, a plurality of aligned molds arranged in two parallel rows, a pair of tracks above said rows of molds, a bridge, means adapted to give said bridge a three-point rolling suspension on said tracks, a rack on said tracks, a pinion on said bridge engaging with said rack and a motor for operating said pinion to control the position of said bridge on said tracks, a carriage, axial means for pivotally supporting said carriage below said bridge, an arcuate crane arm pivotally carried at the axis of its arc on the lower end of said carriage, a rack on the arcuate surface of said arm, a pinion on said carriage adapted to engage with said rack, a motor to control said pinion and thus the position of the crane arm, a vertically extending chuck pivotally mounted at the end of said crane arm and adapted to engage in openings in said molds, and interlocking means on said chuck and in the mold openings.

3. In combination, a plurality of aligned 70 molds arranged in two parallel rows, a pair of tracks above said rows of molds, a bridge, means adapted to give said bridge a three-point rolling suspension on said tracks, a rack on said tracks, a pinion on said bridge 75 engaging with said rack and a motor for operating said pinion to control the position of said bridge on said tracks, a carriage, axial means for pivotally supporting said carriage below said bridge, an arcuate crane arm pivotally carried at the axis of its arc on the lower end of said carriage, a rack on the arcuate surface of said arm, a pinion on said carriage adapted to engage with said rack, a motor to control said pinion and thus the position of the crane arm, a vertically extending chuck pivotally mounted at the end of said crane arm and adapted to engage in 80 openings in said molds, and interlocking means on said chuck and in the mold openings.

3. In combination, a plurality of aligned 90 molds arranged in two parallel rows, a pair of tracks above said rows of molds, a bridge, means adapted to give said bridge a three-point rolling suspension on said tracks, a rack on said tracks, a pinion on said bridge 95 engaging with said rack and a motor for operating said pinion to control the position of said bridge on said tracks, a carriage, axial means for pivotally supporting said carriage below said bridge, a circular rack on the upper portion of said carriage, a pinion on said bridge 100 engaging with said rack and a motor for operating said pinion to control the rotative position of said carriage with respect to said bridge, an arcuate crane arm pivotally carried at the axis of its arc on the lower end of said carriage, a rack on the arcuate surface of said arm, a pinion on said carriage adapted to engage with said rack, a motor to control said pinion and thus the 105 position of the crane arm, a vertically extending chuck pivotally mounted at the end of said crane arm and adapted to engage in openings in said molds, and interlocking means on said chuck and in the mold openings.

4. In combination, a plurality of molds, tracks above said molds, a bridge, means adapted to give said bridge a rolling suspension on said tracks, a rack on said tracks, a pinion on said bridge engaging with said rack and a motor for operating said pinion to control the position of said bridge on said tracks, a carriage, axial means for pivotally supporting said carriage below said bridge, a circular rack on the upper portion of said carriage, a pinion on said bridge 120 engaging with said rack and a motor for operating said pinion to control the rotative position of said carriage with respect to said 125 bridge, an arcuate crane arm pivotally carried at the axis of its arc on the lower end of said carriage, a rack on the arcuate surface of said arm, a pinion on said carriage adapted to engage with said rack, a motor to control said pinion and thus the position of the crane arm, a vertically extending chuck pivotally mounted at the end of said crane arm and adapted to engage in 130 openings in said molds, and interlocking means on said chuck and in the mold openings.

- bridge, an arcuate crane arm pivotally carried at the axis of its arc on the lower end of said carriage, a rack on the arcuate surface of said arm, a pinion on said carriage 5 adapted to engage with said rack, a motor to control said pinion and thus the position of the crane arm, a vertically extending chuck pivotally mounted at the end of said crane arm and adapted to engage in openings in said molds, and interlocking means on said chuck and in the mold openings.
5. In combination, a plurality of molds, tracks above said molds, a bridge, means adapted to give said bridge a rolling suspension on said tracks, means to control the position of said bridge on said tracks, a carriage, axial means for pivotally supporting said carriage below said bridge, means to control the rotative position of said carriage with 10 respect to said bridge, an arcuate crane arm pivotally carried at the axis of its arc on the lower end of said carriage, a rack on the arcuate surface of said arm, a pinion on said carriage adapted to engage with said rack, a motor to control said pinion and thus the position of the crane arm, a vertically extending chuck pivotally mounted at the end of said crane arm and adapted to engage in openings in said molds, and interlocking means on said chuck and in the mold openings.
6. In combination, a plurality of molds, tracks above said molds, a bridge, means adapted to give said bridge a rolling suspension on said tracks, means to control the position of said bridge on said tracks, a carriage, axial means for pivotally supporting said carriage below said bridge, means to control the rotative position of said carriage with 15 respect to said bridge, a crane arm pivotally carried on said carriage, means to control the position of the crane arm, a vertically extending chuck pivotally mounted at the end of said crane arm and adapted to engage in openings in said molds, and interlocking means on said chuck and in the mold openings.
7. In combination a plurality of molds, tracks adjacent said molds, a bridge, means adapted to give said bridge a rolling support on said tracks, means to control the position of said bridge on said track, said means including a reversible motor for driving said bridge, means for automatically slowing the 20 motor down just before each mold station, means for automatically stopping said motor at each mold station and braking means for quickly stopping said motor when no current is supplied to said motor, a carriage, means for pivotally supporting said carriage on said bridge, means for controlling the relative rotative positions of said bridge and said carriage, said means including a reversible motor for rotating said carriage and means for automatically stopping said motor when the carriage 25
- riage is in proper alignment with a mold, an arcuate crane arm pivotally carried at the axis of its arc on the lower end of said carriage, a vertically extending chuck pivotally mounted at the end of said crane arm and 30 adapted to engage in openings in said molds, interlocking means on said chuck and in said mold openings, means to control the position of said crane arm including a reversible motor, means to automatically stop the crane arm in a fully open position, means to automatically stop the crane arm in a fully closed position, means to automatically stop the crane arm in an intermediate position, and means for automatically starting the travel 35 motor to drive the bridge along the tracks to the next mold station when the crane arm stops in the intermediate position.
8. In combination a plurality of molds, tracks adjacent said molds, a bridge, means adapted to give said bridge a rolling support on said tracks, means to control the position of said bridge on said track, said means including a reversible motor for driving said bridge, means for automatically stopping said 40 motor at each mold station, a carriage, means for pivotally supporting said carriage on said bridge, means for controlling the relative rotative positions of said bridge and said carriage, said means including a reversible motor for rotating said carriage and means for automatically stopping said motor when the carriage is in proper alignment with a mold, a crane arm pivotally carried on the carriage, a vertically extending chuck pivotally mounted at the end of said crane arm and adapted to engage in openings in said molds, interlocking means on said chuck and in said mold openings, means to control the position of said crane arm including a reversible motor, means to automatically stop the crane arm in a fully open position, means to automatically stop the crane arm in a fully closed position, means to automatically stop the crane arm in an intermediate position, and means for automatically starting the travel motor to drive the bridge along the tracks to the next mold station when the crane arm stops in the intermediate position.
9. In combination a plurality of molds, tracks adjacent said molds, a bridge, means adapted to give said bridge a rolling support on said tracks, means to control the position of said bridge on said track, said means including a reversible motor for driving said bridge, means for automatically stopping said motor at each mold station, a carriage, means for pivotally supporting said carriage on said bridge, means for controlling the relative rotative positions of said bridge and said carriage, said means including a reversible motor for rotating said carriage and means for automatically stopping said motor when the carriage is in proper alignment with a mold, a crane arm pivotally carried on the carriage, a

chuck pivotally mounted at the end of said crane arm and adapted to engage in openings in said molds, interlocking means on said chuck and in said mold openings, means to control the position of said crane arm including a reversible motor, means to automatically stop the crane arm in a fully open position, means to automatically stop the crane arm in a fully closed position, and means to automatically stop the crane arm in an intermediate position.

10. In combination a plurality of molds, tracks adjacent said molds, a bridge, means adapted to give said bridge a rolling support on said tracks, means to control the position of said bridge on said track, said means including a reversible motor for driving said bridge, means for automatically stopping said motor at each mold station, a carriage, means for pivotally supporting said carriage on said bridge, means for controlling the relative rotative positions of said bridge and said carriage, said means including a reversible motor for rotating said carriage and means for automatically stopping said motor when the carriage is in proper alignment with a mold, a crane arm pivotally carried on the carriage, a vertically extending chuck pivotally mounted at the end of said crane arm and adapted to engage in openings in said molds, interlocking means on said chuck and in said mold openings, means to control the position of said crane arm including a reversible motor, means to automatically stop the crane arm in an intermediate position, and means for automatically starting the travel motor to drive the bridge along the tracks to the next mold station when the crane arm stops in the intermediate position.

40 11. In combination a plurality of molds, tracks adjacent said molds, a bridge, means adapted to give said bridge a rolling support on said tracks, means to control the position of said bridge on said track, a carriage, means for pivotally supporting said carriage on said bridge, means for controlling the relative rotative positions of said bridge and said carriage, said means including a reversible motor for rotating said carriage and means for automatically stopping said motor when the carriage is in proper alignment with a mold, an arcuate crane arm pivotally carried at the axis of its arc on the lower end of said carriage, a vertically extending chuck pivotally mounted at the end of said crane arm and adapted to engage in openings in said molds, interlocking means on said chuck and in said mold openings, means to control the position of said crane arm including a reversible motor, means to automatically stop the crane arm in a fully open position, means to automatically stop the crane arm in a fully closed position, means to automatically stop the crane arm in an intermediate position, and means for automatically starting the

travel motor to drive the bridge along the tracks to the next mold station when the crane arm stops in the intermediate position.

12. In combination a plurality of molds, tracks adjacent said molds, a bridge, means adapted to give said bridge a rolling support on said tracks, means to control the position of said bridge on said track, a carriage, means for pivotally supporting said carriage on said bridge, means for controlling the relative rotative positions of said bridge and said carriage, an arcuate crane arm pivotally carried at the axis of its arc on the lower end of said carriage, a vertically extending chuck pivotally mounted at the end of said crane arm and adapted to engage in openings in said molds, interlocking means on said chuck and in said mold openings, means to control the position of said crane arm including a reversible motor, means to automatically stop the crane arm in a fully open position, means to automatically stop the crane in a fully closed position, means to automatically stop the crane arm in an intermediate position, and means for automatically starting the travel motor to drive the bridge along the tracks to the next mold station when the crane arm stops in the intermediate position.

13. In combination a plurality of molds, tracks adjacent said molds, a bridge, means adapted to give said bridge a rolling support on said tracks, means to control the position of said bridge on said track, a carriage, means for pivotally supporting said carriage on said bridge, means for controlling the relative rotative positions of said bridge and said carriage, a crane arm pivotally carried on the carriage, a vertically extending chuck pivotally mounted at the end of said crane arm and adapted to engage in openings in said molds, interlocking means on said chuck and in said mold openings, and means to control the position of said crane arm including a reversible motor.

14. In combination a plurality of molds, tracks adjacent said molds, a bridge, means adapted to give said bridge a rolling support on said tracks, means to control the position of said bridge on said track, a carriage, means for pivotally supporting said carriage on said bridge, means for controlling the relative rotative positions of said bridge and said carriage, a crane arm pivotally carried on the carriage, means on said crane arm adapted to engage with means in said molds when the crane arm is in the lowered position, and means to control the position of said crane arm including a reversible motor.

15. In combination a plurality of molds, tracks adjacent said molds, a bridge, means adapted to give said bridge a rolling support on said tracks, means to control the position of said bridge on said track, said means including a reversible motor for driving said bridge, means for automatically slowing the

- motor down just before each mold station, means for automatically stopping said motor at each mold station and braking means for quickly stopping said motor when no current is supplied to said motor, a carriage, means for pivotally supporting said carriage on said bridge, means for controlling the relative rotative positions of said bridge and said carriage, said means including a reversible motor for rotating said carriage and means for automatically stopping said motor when the carriage is in proper alignment with a mold, a crane arm pivotally carried on the carriage, a vertically extending chuck pivotally mounted at the end of said crane arm and adapted to engage in openings in said molds, interlocking means on said chuck and in said mold openings, and means to control the position of said crane arm including a reversible motor.
16. In combination a plurality of molds, tracks adjacent said molds, a bridge, means adapted to give said bridge a rolling support on said tracks, means to control the position of said bridge on said track, said means including a reversible motor for driving said bridge, means for automatically slowing the motor down just before each mold station, means for automatically stopping said motor at each mold station and braking means for quickly stopping said motor when no current is supplied to said motor, a carriage, means for pivotally supporting said carriage on said bridge, means for controlling the relative rotative positions of said bridge and said carriage, a crane arm pivotally carried on the carriage, a vertically extending chuck pivotally mounted at the end of said crane arm and adapted to engage in openings in said molds, interlocking means on said chuck and in said mold openings, and means to control the position of said crane arm including a reversible motor.
17. In combination a plurality of molds, tracks adjacent said molds, a bridge, means adapted to give said bridge a rolling support on said tracks, means to control the position of said bridge on said track, a carriage, means for pivotally supporting said carriage on said bridge, means for controlling the relative rotative positions of said bridge and said carriage, said means including a reversible motor for rotating said carriage and means for automatically stopping said motor when the carriage is in proper alignment with a mold, a crane arm pivotally carried on the carriage, a vertically extending chuck pivotally mounted at the end of said crane arm and adapted to engage in openings in said molds, interlocking means on said chuck and in said mold openings, and means to control the position of said crane arm including a reversible motor.
18. In combination a plurality of molds, tracks adjacent said molds, a bridge, means adapted to give said bridge a rolling support on said tracks, means to control the position of said bridge on said track, a carriage, means for pivotally supporting said carriage on said bridge, means for controlling the relative rotative positions of said bridge and said carriage, a crane arm pivotally carried on the carriage, a vertically extending chuck pivotally mounted at the end of said crane arm and adapted to engage in openings in said molds, interlocking means on said chuck and in said mold openings, and means to control the position of said crane arm including a reversible motor.
19. In combination a plurality of molds, tracks adjacent said molds, a bridge, means adapted to give said bridge a rolling support on said tracks, means to control the position of said bridge on said track, said means including a reversible motor for driving said bridge, means comprising fixed cams cooperating with switches on the bridge for automatically slowing the motor down just before each mold station, means comprising fixed cams cooperating with switches on the bridge for automatically stopping said motor at each mold station, a carriage, means for pivotally supporting said carriage on said bridge, means for controlling the relative rotative positions of said bridge and said carriage, said means including a reversible motor for rotating said carriage and means for automatically stopping said motor when the carriage is in proper alignment with a mold, a crane arm pivotally carried on the carriage, a chuck pivotally mounted at the end of said crane arm and adapted to engage in openings in said molds, interlocking means on said chuck and in said mold openings, means to control the position of said crane arm including a reversible motor, means on the crane arm and carriage comprising cooperating cams and switches to automatically stop the crane arm in a fully open position, means on the crane arm and carriage comprising cooperating cams and switches to automatically stop the crane arm in a fully closed position, means on the crane arm and carriage comprising cooperating cams and switches to automatically stop the crane arm in an intermediate position, and means on the crane arm and carriage comprising cooperating cams and switches for automatically starting the travel motor to drive the bridge along the tracks to the next mold station when the crane arm stops in the intermediate position.
20. In combination a plurality of molds, tracks adjacent said molds, a bridge, means

adapted to give said bridge a rolling support on said tracks, means to control the position of said bridge on said track, said means including a reversible motor for driving said bridge, means comprising fixed cams cooperating with switches on the bridge for automatically slowing the motor down just before each mold station, means comprising fixed cams cooperating with switches on the bridge for automatically stopping said motor at each mold station, a carriage, means for pivotally supporting said carriage on said bridge, means for controlling the relative rotative positions of said bridge and said carriage, said means including a reversible motor for rotating said carriage and means for automatically stopping said motor when the carriage is in proper alignment with a mold, a crane arm pivotally carried on the carriage, a chuck pivotally mounted at the end of said crane arm and adapted to engage in openings in said molds, interlocking means on said chuck and in said mold openings, means to control the position of said crane arm including a reversible motor, means on the crane arm and carriage comprising cooperating cams and switches to automatically stop the crane arm in a fully open position, means on the crane arm and carriage comprising cooperating cams and switches to automatically stop the crane arm in a fully closed position, and means on the crane arm and carriage comprising cooperating cams and switches to automatically stop the crane arm in an intermediate position.
